N. W. ORDWAY

TOOL MAKER'S GAUGE

Filed Nov. 28, 1924

INVENTOR
Alpheus W. Ordway,
by
Arthur B. Pendleton
ATTORNEY

UNITED STATES PATENT OFFICE.

NEHEMIAH W. ORDWAY, OF HARTFORD, CONNECTICUT.

TOOLMAKER'S GAUGE.

Application filed November 28, 1924. Serial No. 752,616.

To all whom it may concern:

Be it known that I, NEHEMIAH W. ORDWAY, a citizen of the United States, and a resident of Hartford, in the county of Hartford and State of Connecticut, have invented a new and Improved Toolmaker's Gauge, of which the following is a specification.

My invention relates to the class of instruments commonly employed by tool makers and other mechanics for measuring and gauging purposes, and an object of my invention, among others, is to provide a tool of this class that may be used for various purposes, that shall be simple in construction, and that shall be particularly effective in securing the results desired.

One form of device embodying my invention and in the construction and use of which the objects herein set out, as well as others, may be attained, is illustrated in the accompanying drawings, in which—

Figure 1 is a view in side elevation of my improved tool showing its use in determining the proper angles for the cutting end of a drill.

Figure 2 is an edge view of the same.

Figure 3 is an edge view of the stock.

Figure 4 is an end view of the structure shown in Figure 1.

Figure 5 is a view of a fragment of the stock showing its use with a scaled blade.

Figure 6 is an edge view of the structure shown in Figure 5.

Figure 7 is a detail view of one of the blades illustrated in Figure 4.

Figure 8 is a detail view of the other blade illustrated in the structure of Figure 4.

My invention comprises a stock that is formed to receive various instruments in connection with which gauges and measuring devices of various sorts may be employed for different purposes, thus enabling the tool to be put to a wide variety of uses.

In the accompanying drawings the numeral 10 denotes the stock as a whole comprising a web 11 bounded by a side face 12 and an end face 13, said faces being located at right angles each to the other and being of considerable width to enable the stock alone to be used as a square or in connection with blades to be hereinafter described to provide a square of increased dimensions.

A slot 14 is formed in the end of the stock extending in the direction of width of such stock and this slot is adapted to receive various instruments to be employed for different

purposes. A narrow recess 15 opens out from the slot 14 and along and through the face 12, as shown in Figure 3 of the drawings, the back of this recess being tapered from the face 12 to the point where it meets the slot 14.

The construction of the stock thus far described is especially adapted for use with taper determining blades 16—17, each of which comprises a shank 18 or 19 terminating in a pointed tapered head 20 or 21. The tapers of the edges 22 and 23 extend in different directions so that surfaces terminating in a point may be gauged. In the illustration shown herein the blades are arranged to gauge the cutting end of a drill, the two blades being so disposed that their meeting edges form a notch 24 by means of which it may be readily determined whether the two sides of the drill end are formed at the same angle and also whether the point is in the center. By moving the blade 17 into the stock and the blade 16 farther out of the stock, either or both, it will be noted that a tapered surface comprising a recess or notch may be gauged.

In this form of the structure the shanks 18 and 19 rest against each other in the slot 14, said slot being preferably of a width substantially twice that of the narrow recess 15.

In the form of the device illustrated in Figures 5 and 6 a blade 25 is employed that is preferably the dimensions of the slot 14 and such blade may be provided with scales 26 by means of which different measurements may be obtained, the device thus assembled satisfactorily answering for one of its purposes as a depth gauge.

The shank 18 of the blade 16 may be provided with a lug 27 projecting outwardly to engage the edge of the stock at the side of the slot 14, and thus hold the blade 16 against endwise movement if desired.

It will be noted that the beveled or tapered edges 22—23 are so arranged that drills of various sizes and of a considerable width may be readily and accurately gauged.

In accordance with the provisions of the patent statutes I have described the principles of operation of my invention, together with the device which I now consider to represent the best embodiment thereof; but I desire to have it understood that the device shown is only illustrative, and that the invention may be carried out by other means

and applied to uses other than those above set out.

I claim:—

1. A stock having a straight edge with a slot extending thereto with its lengthwise dimension at right angles to such edge, and two blades fitting said slot and extending lengthwise therein and having cooperating tapered edges.
- 10 2. A stock having two straight edges located at right angles to each other and with a slot extending into said stock lengthwise of one of said edges and parallel therewith, and two blades fitting said slot and having 15 cooperating tapered edges.
- 20 3. A stock having a straight edge with a slot extending thereto at right angles to said edge, and two flat blades fitting said slot with their flat faces resting against each other and the edge of each of said blades being provided with a tapered portion cooperating with the tapered portion of the other blade.
- 25 4. A stock having a straight edge with a slot extending thereto at right angles to

said edge, said slot having a beveled portion, and a blade fitting said slot and having a beveled portion fitting the beveled portion of said slot to locate an edge of said blade at right angles to said straight edge of the stock.

5. A stock having a straight edge with a slot extending thereto at right angles to said edge, said slot having a beveled back portion forming a recess narrower than said slot, and a blade fitting said slot and having a beveled portion fitting the beveled portion of said slot to locate an edge of said blade at right angles to said straight edge of the stock.

40 6. A stock having a straight edge with a slot extending thereto with its lengthwise dimension at right angles to said edge, and two flat blades fitting said slot and extending lengthwise thereto with their flat faces resting against each other and the edges of said blades being provided near their ends 45 with cooperating oppositely tapered portions.

NEHEMIAH W. ORDWAY.
